ENGINE STARTING MECHANISM

Raymond P. Lansing, Montclair, N. J., assignor
to Bendix Aviation Corporation, South Bend,
Ind., a corporation of Delaware

Application January 12, 1939, Serial No. 250,655

9 Claims. (Cl. 185—41)

This invention relates to internal combustion engines, and particularly to the starting thereof. Internal combustion engines are commonly started by means of devices having rotatable elements, one of which (referred to as an engine engaging member) is movable to engage a rotatable extension of the engine crankshaft, or crankshaft connected part, to impart initial rotary movement thereto, in synchronism with the delivery of fuel and ignition current to the engine cylinders. In some installations the rotatable engine-engaging member is electrically driven as in my Patent No. 1,962,397, granted June 12, 1934, while in others the rotative effort is first stored in a spring (as by hand-winding thereof) and then delivered upon release of a latch or equivalent means for holding the spring fully wound. My Patent No. 1,936,554 exemplifies this class of starters.

Limitations upon the strength of the ordinary person place corresponding limitations upon the size of spring that may be employed in such a spring starter. The power developable in this fashion is accordingly limited to such an extent as to render such a starter effective only for the starting of engines of comparatively low compression-resistance to initial rotation. For engines of higher capacity, therefore, spring starters of the character shown in my patent above identified have not heretofore been employed.

If, in such a spring starter, means were to be provided whereby a strong spring could be placed in stress by power operation, there would still be the problem of holding the spring in stress and releasing such holding means at the moment when cranking of the engine became desirable. With a high capacity spring it would be very difficult, as well as hazardous, to operate such holding means, whether to hold the spring, to release it, or both.

In the present invention this problem is solved by combining the spring stressing means, the spring holding means, and the spring releasing means in a single instrumentality; and it is accordingly an object of the present invention to provide a spring starter wherein such a single instrumentality acts as the spring stressing means, the spring holding means, and the spring releasing means.

A second object of the invention is to provide, in such a spring starter, a single instrumentality involving a spring actuating cam and cam follower constructed and related, to each other and to the spring, in such manner as to facilitate

storage of energy in the spring and the subsequent release thereof.

A third object of the invention is to provide, in such a spring starter, a single instrumentality involving elements constructed and related, to each other and to the spring, in such manner as to produce spring stressing and spring release as consecutive steps in a single, uninterrupted operation.

A fourth object of the invention is to provide, in such a spring starter, a single instrumentality involving spring stressing, holding and releasing elements actuated by a common prime mover related thereto and controlled thereby in such manner as to produce de-energization of the prime mover drive automatically, and in timed relation to the delivery to the engine-engaging member of the engine starting energy.

A fifth object of the invention is to provide, in such a spring starter, transmission mechanism between the spring and engine-engaging member constructed and related thereto in such manner as to cause the engine-engaging member to move into engine-engaging position in response to release of the spring, and out of engine-engaging position after full expansion of the spring, and prior to de-energization of the electric motor or other prime mover.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing:

Fig. 1 is a longitudinal sectional view of a device embodying the invention;

Fig. 2 is a diagrammatic view of the prime mover in its relationship to associated parts; and

Fig. 3 is a view of the preferred form of control cam.

In the drawing reference character 5 designates a prime mover in the form of an electric motor, and reference character 6 designates an engine-engaging member movable into engagement with engine member 7 and adapted to transmit starting torque thereto in response to expansion of the spring 8. Interposed between spring 8 and the screw-threaded rearward extension 9 of member 6, is a thrust and motion translating element 10 having an internally threaded portion 11.

11 coating with the screw 9 to first move the latter forward and then produce rotation thereof in response to release of the energy previously stored in spring 8 by the means now to be described.

12 The means for storing energy in spring 8, and then releasing said energy to start the engine, includes a pair of identical cam elements 12, 13 and a corresponding pair of cam followers 14, 15, 10 the latter being in the form of rollers mounted on a common cross-head 16 whose intermediate portion receives one end 17 of a connecting rod 18 whose opposite end is threaded to receive a nut 19 adjustably holding said rod 18 and the motion translating element 10 in assembled, working relationship. The cams 12, 13 are integral with a drive shaft 21 adapted to be rotated either by a hand-crank 22 or by the previously described electric motor 5; the connections therebetween 20 including, as shown, a worm 24 on the outer end of the motor shaft, a worm wheel 25 driven by the worm at reduced speed, and a uni-directional clutch 26 permitting rotation of the shaft 21 by hand-crank 22 without opposition from the worm 25 and gear 24, 25, whenever hand operation is desired.

30 The cams 12, 13 are shaped and mounted in such manner as to facilitate a gradual storage of energy in the spring 8 and a far more rapid delivery of the energy back to the motion translating element 10, also to permit automatic release of the stored energy prior to interruption of the rotation of the cams. To assure uninterrupted flow of current to the motor 5 prior to such release of the energy, and also prior to completion of a predetermined arc of rotation of the cams, sufficient to return the engine-engaging member 6 to the disengaged position shown in the drawing, I provide automatic circuit-breaking means in 35 the form of a ring 31 rotatable with worm wheel 25 and having a projection 32 adapted to separate switch element 33 from switch element 34, with which it is normally engaged, when the cams reach the position in which radial line o—x (Fig. 40 45 3) intercepts the center of the cam follower, which will then be substantially in the position shown at 15x. In this 15x position the spring 8 will be slightly recompressed by virtue of the return movement of the cam followers, to the extent indicated in Fig. 3.

50 The motor is initially energized by closure of hand-switch 37, said switch 37 being in the motor circuit, as is also the switch 33, 34; it being understood that the operator will hold said hand-switch 37 in closed position until the motor has been sufficiently energized to carry the controller 32 away from switch element 33, whereupon a circuit from source 40 is completed independently of the switch 37, so that the switch 37 can then 55 be re-opened without causing stoppage of the cycle of operation. The continued rotation of the motor swings cams 36 in a clockwise direction and thus causes retraction of the cam followers 60 and further re-compression of spring 8. When this re-compression of spring 8 has been completed the outer points 36 of the cams will have reached a position wherein further rotation frees the rollers 14, 15 from contact therewith, whereupon spring 8 expands and delivers the stored 65 energy to the engine, the rollers 14, 15 being carried along with rod 18, to assume positions, with respect to the cams, corresponding to that indicated by the full-time showing of roller 15 in 70 75 Fig. 3. From this point the roller is returned to

the 15x position prior to deenergization of the motor, as above pointed out.

When the freeing of the rollers 14, 15 occurs, the resulting expansion of the spring 8 causes, first, a longitudinal movement of the engine-engaging member 6, said movement being due to the combined effect of the internally formed threads and the externally formed splines on the motion translating thrust element 10—the said splines being in engagement with corresponding splines 10 on the inner cylindrical surface of fixed element 20, against the outer end of which the flange 30 of engine-engaging member 6 normally abuts. As the spring continues to expand—the engagement of the members 6 and 7 being completed by 15 the first stage of such expansion—element 18 moves further forward along the splines of fixed element 20, thereby causing continued rotary (cranking) movement of the now engaged parts 6 and 7, until all stored energy has been delivered 20 thereto.

What I claim is:

1. The combination with an engine-engaging member, a helically wound spring, and a driving connection therebetween, of means for compressing said spring, said means including a rotatable cam operating upon said spring in such manner that the expansion of the spring, for delivery of starting energy to the engine-engaging member, follows immediately upon completion of the compression thereof, and prior to cessation of rotation of the cam, and means for maintaining said cam in rotation until the spring has been fully compressed, released for expansion, and partially compressed again, said last-named means including an electric motor, a source of current, and a circuit that remains closed until said cam reaches a predetermined position in its cycle of rotation. 30

2. The combination with an engine-engaging member, a spring, and a driving connection therebetween, of means for compressing said spring, said means including a rotatable controller operating upon said spring in such manner that the expansion of the spring, for delivery of starting energy to the engine-engaging member, follows 40 immediately upon completion of the compression thereof, and prior to cessation of rotation of the controller, and means for maintaining said controller in rotation until the spring has been fully compressed, released for expansion, and partially compressed again, said last-named means including an electric motor, a source of current, and a circuit that remains closed until said controller reaches a predetermined position in its cycle of rotation. 50

3. The combination with an engine-engaging member, a helically wound spring, and a driving connection therebetween for producing axial (engine-engaging) and then rotary movement of said engine-engaging member, of means for compressing said spring, said means including a rotatable cam operating upon said spring in such manner that the expansion of the spring, for delivery of starting energy to the engine-engaging member, follows immediately upon completion of the compression thereof, and prior to cessation of rotation of the cam, and means for maintaining said cam in rotation until the spring has been fully compressed, released for expansion, and partially compressed again, said last-named means including an electric motor, a source of current, and a circuit that remains closed until said cam reaches a predetermined position in its cycle of rotation. 60

4. The combination with an engine-engaging 7

member, a spring, and a driving connection therebetween for producing axial (engine-engaging) and then rotary movement of said engine-engaging member, of means for compressing said spring, said means including a rotatable controller operating upon said spring in such manner that the expansion of the spring, for delivery of starting energy to the engine-engaging member, follows immediately upon completion of the compression thereof, and prior to cessation of rotation of the controller, and means for maintaining said controller in rotation until the spring has been fully compressed, released for expansion, and partially compressed again.

5. The combination with an engine-engaging member, a spring, and a driving connection therebetween for producing axial (engine-engaging) and then rotary movement of said engine-engaging member, of means for compressing said spring, said means including a rotatable controller operating upon said spring in such manner that the expansion of the spring, for delivery of starting energy to the engine-engaging member, follows immediately upon completion of the compression thereof, and prior to cessation of rotation of the controller, and means for maintaining said controller in rotation until the spring has been fully compressed, released for expansion, and partially compressed again, said last-named means including an electric motor, a source of current, and a circuit that remains closed until said controller reaches a predetermined position in its cycle of rotation.

6. The combination with an engine-engaging member, a helically wound spring, and a driving connection therebetween, of means for compressing said spring, said means including a rotatable cam operating upon said spring in such manner that the expansion of the spring, for delivery of starting energy to the engine-engaging member, follows immediately upon completion of the compression thereof, and prior to cessation of rotation of the cam, means for maintaining said cam in rotation until the spring has been fully compressed, released for expansion, and partially compressed again, said last-named means including an electric motor, a source of current, a circuit that remains closed until said cam reaches a predetermined position in its cycle of rotation, manual means for rotating said cam, and a one-way driving connection between said motor and cam, including one race that remains stationary whenever said manual means is operated.

7. The combination with an engine-engaging member, a spring, and a driving connection therebetween, of means for compressing said spring, said means including a rotatable controller operating upon said spring in such manner that the expansion of the spring, for delivery of starting energy to the engine-engaging member, follows immediately upon completion of the com-

pression thereof, and prior to cessation of rotation of the controller, means for maintaining said controller in rotation until the spring has been fully compressed, released for expansion, and partially compressed again, said last-named means including an electric motor, a source of current, a circuit that remains closed until said controller reaches a predetermined position in its cycle of rotation, manual means for rotating said controller, and a one-way driving connection between said motor and controller, including one race that remains stationary whenever said manual means is operated.

8. The combination with an engine-engaging member, a helically wound spring, and a driving connection therebetween for producing axial (engine-engaging) and then rotary movement of said engine-engaging member, of means for compressing said spring, said means including a rotatable cam operating upon said spring in such manner that the expansion of the spring, for delivery of starting energy to the engine-engaging member, follows immediately upon completion of the compression thereof, and prior to cessation of rotation of the cam, means for maintaining said cam in rotation until the spring has been fully compressed, released for expansion, and partially compressed again, said last-named means including an electric motor, a source of current, a circuit that remains closed until said cam reaches a predetermined position in its cycle of rotation, manual means for rotating said cam, and a one-way driving connection between said motor and cam, including one race that remains stationary whenever said manual means is operated.

9. The combination with an engine-engaging member, a spring, and a driving connection therebetween for producing axial (engine-engaging) and then rotary movement of said engine-engaging member, of means for compressing said spring, said means including a rotatable controller operating upon said spring in such manner that the expansion of the spring, for delivery of starting energy to the engine-engaging member, follows immediately upon completion of the compression thereof, and prior to cessation of rotation of the controller, means for maintaining said controller in rotation until the spring has been fully compressed, released for expansion, and partially compressed again, said last-named means including an electric motor, a source of current, a circuit that remains closed until said controller reaches a predetermined position in its cycle of rotation, manual means for rotating said controller, and a one-way driving connection between said motor and controller, including one race that remains stationary whenever said manual means is operated.
